TREATING HYDROCARBON OILS

Otto Behimer, Port Arthur, Tex., assignor, by
mesne assignments, to The Texas Company,
New York, N. Y., a Corporation of Delaware

Application August 13, 1925. Serial No. 49,915

1 Claim. (Cl. 196—58)

This invention relates to the conversion of higher boiling hydrocarbons into lower boiling ones for the production of gasoline and similar products.

One of the objects of the invention is to provide a method of cracking hydrocarbon oils that is adapted to be operated in a given apparatus for extended periods of time thus avoiding the disadvantages incident to many existing systems which require frequent shut-downs for the purpose of removing carbon and coke accumulated during a run. My experiments have shown that cracking or molecular decomposition of hydrocarbons can be carried on for a time without the formation of carbon. It appears that in the first stages of the cracking operation the hydrocarbon compounds are broken down to yield lighter or lower boiling constituents, such as gasoline, some intermediate fractions and certain higher boiling or heavier products of greater molecular weight than any of the constituents in the original oil treated. These heavier products appear to be polymerized constituents and are readily converted into carbon or coke upon the further application of heat. My experiments indicate clearly that it is these polymers or heavy carbon-forming compounds produced in the cracking reaction that in common methods of operation are decomposed to form free carbon. I have found that by arresting the decomposition at or before the critical point at which these heavy carbon-forming oils are converted into carbon or coke that higher boiling hydrocarbons may be converted into lower boiling ones without the production of any material quantity of carbon or coke. In this way it is possible to operate in a given apparatus for long periods of time.

Broadly and generally my invention contemplates passing oil through a cracking zone and arresting the decomposition at approximately the critical point at which free carbon is formed. It is to be observed that in the practice of my invention I do not carry the cracking operation, as applied to a given charge of oil through the converter, to completion but on the contrary subject the oil to cracking until the oil reaches that stage of decomposition at which free carbon is produced and then immediately reduce the temperature of the oil so as to prevent further decomposition.

So far as I am aware there is at the present time no effective method for separating the polymers or high carbon-forming products from the rest of the oil in the cracking system. It is

true that in some of the existing cracking systems oil or residue is withdrawn from the converter during a run but such a method of operation does not insure that all the high-carbon forming oils will be removed from the converter, because these products are in solution with the rest of the oil in the converter. My experience with prior cracking processes has been that it is impossible in a continuous process to effect a clean separation between the polymers or high carbon-forming oils and the rest of the oil and that as a run continues, even though liquid be regularly withdrawn from the cracking zone in the customary manner, there is a tendency for these carbon-forming products to collect in the cracking zone causing increased quantities of carbon and coke to accumulate therein. One of the primary objects of my invention is to provide a continuous method of operation of such nature that the heavy carbon-forming oils may be separated from the rest of the oil before being decomposed into carbon. In practicing the invention the polymers or high carbon-forming compounds are removed from the cracking zone practically as soon as formed and are immediately separated from the rest of the oil.

I have found that hydrocarbon oils vary considerably in carbon-forming capacity. Thus in the case of some oils carbon begins to form as soon as the oil has been decomposed sufficiently to yield about 5% or 10% of gasoline. With other oils it is possible to produce in a batch operation 20% or 30% or even more gasoline without any appreciable formation of carbon, provided care is taken in designing the heating apparatus so as to avoid, or at least reduce to a minimum, localized overheating and resultant carbonization. In practicing my invention I subject a given oil in passage through the converter to that degree or extent of decomposition, which has been determined by experiment can be applied to such oil without any appreciable formation of carbon and then remove the oil from the cracking zone. The process is preferably conducted in a continuous manner, the charging stock being passed through the cracking zone at such a rate that the required degree of cracking will take place and the oil being then continuously removed from the cracking zone. The time of travel of the oil through the cracking zone is so regulated that the oil will be cracked to the critical point of carbon precipitation and the oil is then rapidly removed from the cracking zone.

In accordance with one aspect of the inven-

tion the oil after having been subjected to the required degree of cracking is then distilled to remove the heavy polymers as a tar or residue and the resultant vapors are fractionated to 5 separate out as a distillate the lower boiling product (e. g. gasoline) desired while the heavier condensate obtained is preferably commingled with the initial charging stock for cyclic passage through the converter. The condensed 10 product which is returned to the converter may for convenience be termed cycle oil. This product is substantially free from the heavier polymers or high carbon-forming oils, since it has been separated therefrom by distillation, and 15 thus may with advantage be returned to the cracking zone so that it may ultimately be converted to gasoline or other light product desired.

I preferably employ the cycle stock in proportions somewhat in accordance with the carbon-forming qualities of the initial charging stock 20 used. Thus in the case of an oil that yields carbon with say only 10% of cracked gasoline the cycle stock is used in maximum proportions, while with an oil that does not yield carbon 25 until say 25% of gasoline is formed the proportions of cycle stock used may be considerably less. In general, the greater the carbon-forming capacity of the oil, that is, the greater the readiness with which it carbonizes, the greater 30 the proportion of cycle stock employed, and the more resistant the oil is to carbonization, the smaller the proportion of cycle oil required. In most cases it is desirable to so operate as to provide quantities of cycle stock in excess of 35 the amount of initial charge. And the cyclic return of oil to the cracking zone, in quantities exceeding that of the initial charge, is an important feature of one phase of the invention.

In accordance with my invention the cracking 40 operation is preferably carried on under a comparatively high pressure so that when decomposition is arrested by a lowering of the temperature, the pressure also may be reduced to effect distillation whereby the heavy polymers 45 or high carbon-forming compounds may be removed from the system as a residue while substantially all of the remaining products are vaporized. The vapor products contain the gasoline or naphtha desired and the cycle oil which is separated out and returned to the converter 50 to dilute the initial charge.

An important feature of my invention consists in carrying on the cracking or decomposition of the oil while in motion and under such conditions that the decomposition may be terminated at the precise point desired. Thus the oil being converted may be transmitted through a tubular converter or conduit of restricted cross section, the rate of flow of the oil being so regulated 55 with respect to its particular composition and the temperature employed that the desired extent of decomposition is obtained when the oil reaches the end of the conduit. The resulting products are thereupon rapidly discharged into another vessel wherein the conditions are so altered that further decomposition is arrested or retarded. Best results and economy of operation are obtained by having a high rate of flow through the converter and maintaining a high 60 rate of decomposition.

In existing cracking processes it is customary for the residue, commonly referred to as "pressure bottoms", to contain quantities of gasoline, and also kerosene and gas oil fractions 75 suitable for rerunning in the pressure stills,

and in order to recover these valuable fractions from these residues it has been common practice to remove the pressure still residues from the cracking units and subsequently distill these residues in separate distilling equipment. It is an important object of my invention to provide a continuous cracking and distilling process in which no subsequent distillation of the pressure bottoms is necessary, the oil being converted to gasoline and tar or residue substantially free from lighter products, in one complete continuous operation, as is hereinafter more fully set forth.

For the purpose of describing the invention in detail reference will now be had to the accompanying drawing which is a diagrammatic sectional elevation of one form of apparatus adapted for the practice of the invention and constituting an embodiment thereof. 10 indicates a furnace which may be an oil fired or gas fired furnace and which is adapted to supply high temperature heat to a coil 11. The furnace is provided with a flue 12 which leads to a chamber 13 containing a cracking coil 14. The flue 12 may be equipped with a damper to regulate the passage of spent combustion gases from the furnace 10 to the heating chamber 13, and may also be equipped, if desired, with auxiliary burners 15 for supplying additional heat to the gases leaving the furnace 10. The heating chamber 13 may well be arranged to accommodate, in addition to the cracking coil 14, a pre-heating or economizer coil 16 arranged to be heated by the spent gases that have been used in heating the coil 14.

The oil to be treated is drawn from a suitable source by a pump 17 and charged through a line 18 to such preheating or heat exchange elements as may be desired. Thus a portion or all of the oil may be charged through an exchanger supplied with the heat from tar or residue obtained in the process; or the charge or a portion of it may be brought into heat exchange with vapors evolved in the process. Charging stock may, for example, be introduced 115 into an apparatus employed in dephlegmating or fractionating the vapors, the charge thus being preheated and at the same time serving as a cooling or reflux medium to aid in the condensation or fractionation of the vapors. It is 120 of course desirable to preheat the charge by some such heat exchange system but for simplicity of illustration the pipe 18 is shown as communicating directly with the economizer coil 16. A conduit 19 connects the economizer coil 16 with the heating coil 11. The function of the coil 11 is to supply the oil with a material quantity of the heat required for the cracking operation and it is generally preferable to heat 125 the oil in this coil to a temperature approximating a cracking temperature. An outlet pipe 20 conducts the oil from the heating coil 11 directly to the cracking or reaction coil 14. Here the oil is removed from the direct application 130 of furnace heat, such as is supplied to the coil 11 in the furnace 10, the heat required for maintaining the oil in the coil 14 at the desired cracking temperature being supplied by the flue 13.

gases passing through the flue 12 together with such additional heat, supplied by the burners 15, as may be desired. If desired, the chamber 13 may be lightly fired, but it is generally preferable to rely on convected heat, that is, heat supplied by hot gases entering the chamber, for 145 150

maintaining the coil 14 at the desired cracking temperature.

A pipe 21 is adapted to conduct the oil from the cracking coil 14 to the separating drum or still 22. The pipe 21 may terminate in a pipe 21a extending within the still 22 so that the heat of the fluids passing through this pipe may be utilized to effect distillation without, however, coming into direct contact with the liquid collected in the lower portion of the still. The liquid obtained in the still 22, which may be withdrawn by means of the tar line 23, is substantially free from contamination with the lighter products contained in the fluid conveyed to the still. The still 22 may also be equipped with a steam line 22a for supplying steam to assist in the distillation and to produce agitation of the contents so as to maintain in admixture with liquid being withdrawn any carbon or coke formed and prevent coke deposits in the still. Mechanical means may be employed, if desired, to stir or agitate the contents of the still.

The separating drum or still 22 is provided with a vapor line 24 for conducting the vapors to suitable fractionating equipment 25 which may be a packed tower, bubble tower, or the like. The fractionating tower is preferably equipped with a vapor line 26 leading to a reflux condenser 27 provided with a cooling box 27a. The reflux condenser may be cooled in any convenient manner. Thus for example the charging stock or a portion thereof may be admitted to the cooling box 27a and then either introduced into the fractionating tower 25 or admitted to other heat exchange elements or passed directly to the coil 16 or coil 11. A reflux line 28 is provided to conduct reflux or condensate from the reflux condenser 27 to the fractionating tower 25. A vapor line 29 extends from the reflux condenser to a condenser coil 30 and a receiving drum 31 is provided for receiving distillate obtained from the condenser 30. The receiving drum is preferably equipped with a valved gas outlet 32 and a valved distillate outlet 33.

A pipe 34 is adapted to supply liquid collected in the fractionating device 25 to a hot oil pump 35 which serves to return this liquid to the heating coil 11 through the line 36. The liquid thus returned to the heating coil 11 comprises insufficiently converted fractions or fractions of higher boiling point than that desired in the ultimate distillate and when the charging stock is admitted into the fractionating tower 25 the liquid thus collected therein and pumped to the coil 11 by the pump 35 consists of a mixture of preheated charge and condensed vapors. A bypass line 37 connecting the pipes 23 and 34 may be provided so that liquid collected in the drum or still 22 may be cycled back to the heating coil 11. This is a desirable expedient when the apparatus is being brought under operating conditions, although in the normal operation of the process the line 37 is not used after operating conditions have been established.

In practicing the invention with the apparatus illustrated the oil to be converted is charged through the pipe 18 and economizer coil 16 into the heating coil 11 wherein the oil is heated to approximately a cracking temperature. The oil in transit through the coil 11 may be heated so that it is discharged therefrom at a somewhat higher cracking temperature than is desired to be maintained in the cracking coil 14. The higher the oil is heated in the heating coil 11 the lower the temperature required in the heat-

ing chamber 13 and the less the heat differential between the chamber 13 and oil in the coil 14 with the consequent reduction in liability of locally overheating the coil 14 and causing excess localized decomposition therein. It is preferable to so regulate the length of the time that a given portion of oil is in the coil 11 that there will be little or no decomposition of the oil while in this coil. The oil is then passed into the cracking coil 14 where practically all the decomposition takes place. It is desirable to maintain the oil in the coils 11 and 14 under a considerable pressure so as to retard vaporization therein.

The temperatures and pressures used vary with the particular oils operated on and with the particular products desired. In general, it is not desirable to use pressures materially below 200 lbs. and no particular advantage is to be gained by using pressures in excess of around 2000 lbs. The oil in transit through the coil 11 is generally raised to temperatures approximating 800° F. to 900° F. Ordinarily a temperature around 850° F. in the outlet of the coil 11 will be found most satisfactory. The temperatures used in the cracking coil 14 will generally run from about 850° F. to 1000° F., the preferred temperature being approximately 900° F.

As decomposition is carried on in the coil 14 with resultant production of heavy polymerized products, which as has heretofore been explained are readily decomposed to form free carbon, the necessity of avoiding any material decomposition of these products is apparent. By reason of the fact that the bulk of the heat required for the cracking operation is supplied to the oil while in passage through the coil 11 it is possible to supply to the oil, while in the coil 14, the additional amount of heat required for maintaining the oil at the desired cracking temperature without having an excessive heat gradient between the heat supplying medium and the oil in the coil. Thus the bulk of the heat having been supplied by the high temperature furnace 10 before the oil leaves the coil 11, the remainder of the heat may readily be provided by means of the hot gases conducted by the flue 12. The difference in temperature between the heated gases about the coil 14 and the oil contained therein should be comparatively small so that the danger of locally overheating any portions of the coil is practically eliminated.

The length of the coil 14 is so arranged with respect to the products it is desired to treat and with respect to the velocity at which it is desired to charge the oil through the system, that the oil will be discharged from the coil into the still or separating drum 22 before any material portion of the heavy polymers is decomposed into free carbon.

The resulting products pass through the line 21 and thence into the drum or still 22. The valve in the line 21 is so regulated as to effect a substantial drop in pressure in the still 22. The pressure drop should be such that practically all of the fluid discharged through the pipe 21, except the heavy polymerized products, will be vaporized in the still. These polymers are practically non-vaporizable, that is, in the sense that they are not vaporizable as such; heating them merely decomposes them into carbon and gas. Thus by dropping the pressure in the still the vaporizable constituents may be removed as a vapor and the non-distillate polymers withdrawn from the system as a tar or residue through the line 23. The vapors from the con-

duit 24 are fractionated in the fractionating apparatus 25 so as to take off in the form of vapor through the line 29 the gasoline or naphtha distillate desired while the heavier products are collected at the bottom of the fractionating device and are returned by the pump 35 to the coil 11 for retreatment.

In a specific example of my invention equipment is designed to produce gasoline distillate, 10 collected in the tank 31, at the rate of 10 barrels per hour. The cracking coil 14 is a 3 inch coil about 4000 feet long. The oil to be converted is a heavy kerosene and the oil passing through the cracking coil 14 is held at a temperature of 15 about 900° F. under around 1000 pounds pressure. The oil charge is pumped through the heating coil 11 and cracking coil 14 at the rate of about 67 barrels per hour, 16 barrels consisting of initial charge introduced by the pump 17, 20 and about 51 barrels consisting of the reflux condensate obtained from the fractionating device 25. At this rate of charging about 15 minutes is required for passage through the cracking coil 14 of a unit volume of oil. Heavy tar comprising 25 the carbon-forming polymers is withdrawn from the still 22 at the rate of about 5 barrels per hour. The yield of gasoline distillate, collected in the receiver 31 is approximately 66% of the initial charge.

30 It is to be understood that the foregoing specific example is given merely for illustrative purposes. The various factors as to the dimensions of the equipment used and the conditions of operation will vary within comparatively wide limits. The temperatures employed in the cracking coil, the temperatures of the furnace, the length of the coil, its diameter, the rate of charge through the coil—these and other factors are so arranged and regulated with respect 40 to the particular oil being treated as to produce the desired decomposition—to give the maximum yield of gasoline with the minimum production of carbon.

45 In general the oil is passed through the cracking coil 14 at such a rate of speed that from 10 to 30 minutes is required for such passage; ordinarily the time of travel will approximate 15 minutes. It is to be noted that the time factor varies considerably with different oils; 50 with some oils, such for example as some of the Oklahoma crude derivatives it is possible to carry on a very high degree of cracking without decomposition of the polymers into carbon, and with other oils, such for example as products from certain Mexican crude and Gulf Coast crudes carbon formation begins at a very early point in the cracking reaction.

55 The proportions of reflux condensate or back-trap which are cycled through the cracking zone will vary considerably with the particular type of oil used and with the specific conditions of operation employed. As examples of proportions found suitable when using a fraction of crude petroleum known commercially as gas oil it may be stated that in producing a yield of 65 gasoline constituting approximately 66% of the initial charge and with a conversion into gasoline of 10% per volume put through the cracking zone the ratio of initial charge to cycle oil

was about 1:6; with the same ultimate yield of gasoline but with 15% conversion per volume put through the ratio was about 1:3, with 20% conversion per volume put through the ratio was about 1:2, with 25% conversion per volume put through the ratio was about 1:1% and with 30% conversion per volume put through the ratio was about 1:1%. It is to be observed that in each of these specific examples the yield of gasoline on the basis of the initial charge was 66% which, so far as I am aware, is a greater yield than that obtained by any commercially known cracking equipment.

80 The invention is particularly well adapted for the conversion into gasoline or naphtha of kerosene stocks and the lighter gas oils, the conversion of which is attended with especial difficulty in most of the existing cracking processes, 85 but it may also be applied to the conversion of heavier stocks.

85 Although the preferred embodiment of the invention has been set forth in connection with apparatus having a particular construction and arrangement of parts and mode of operation, it is obvious that various changes and modifications may be made therein, while securing to a greater or less extent some or all of the benefits of the invention, without departing from the spirit and scope thereof. Therefore, only such 95 limitations should be imposed as are indicated 100 in the appended claim.

I claim:

95 The process of converting higher boiling hydrocarbon oils into lower boiling hydrocarbon oils which comprises passing the oil to be converted in admixture with condensate oils derived from previous conversion treatment in continuous flow in a restricted stream through a heating zone in which the oil mixture is heated rapidly to a high cracking temperature, continuing the flow of oil in a restricted stream with substantially undiminished velocity through a confined passageway in a further heating zone, where it is heated only sufficiently to maintain 100 its cracking temperature without substantially increasing in temperature, the time of travel of the oil through said second heating zone being such as to secure a substantial conversion thereof to the desired low boiling products without substantial formation and deposition of free carbon, maintaining superatmospheric pressure on the oil in its flow through said heating zones, reducing the pressure on the oil directly on leaving the second heating zone and passing it in 105 indirect heat conductive contact with a body of unvaporized oil products in an enlarged chamber and thereupon discharging the heated oil mixture into said enlarged chamber, whereby its 110 unvaporized constituents are admixed with the unvaporized oil present in said chamber and said mixture is maintained at a high temperature to effect separation of the vaporizable constituents, 115 separating vapors released in said chamber, cooling them to condense constituents heavier than the desired low boiling products and returning 120 such condensate to admix and pass with fresh oil in the stream entering the heating zones.

125 OTTO BEHIMER.
